UNITED STATES PATENT OFFICE.

SAMUEL H. MOORE AND EDWARD Y. MOORE, OF CHICAGO, ILLINOIS.

IMPROVEMENT IN DOOR-HANGERS.

Specification forming part of Letters Patent No. 177,654, dated May 23, 1876; application filed April 29, 1876.

To all whom it may concern:

Be it known that we, SAMUEL H. MOORE and EDWARD Y. MOORE, of Chicago, in the county of Cook and State of Illinois, have invented certain new and useful Improvements in Barn-Door Hangers; and we do hereby declare that the following is a full, clear, and exact description thereof, which will enable others skilled in the art to which it appertains to make and use the same, reference being had to the accompanying drawings, and to the letters of reference marked thereon, which form a part of this specification.

The nature of our invention consists in the novel construction and arrangement of a barn-door hanger, combined with a non-rotating box of peculiar construction, whereby only the friction-rollers and wheel move in using the device, as will be hereinafter more fully explained and definitely claimed.

In the annexed drawing, Figure 1 is a rear view, with wheel and cap partly removed. Fig. 2 is a central vertical section. Fig. 3 is an inside plan view of the wheel, and Fig. 4 is an inside plan view of the cap.

A represents the cast-metal strap or plate, which is to be fastened on the side of the door, and which may be made of any suitable form and dimension. On one side, at the upper end of the strap A, is formed a circular rim, B, having an aperture, *h*, on its under side, of such size that a wheel placed within the rim will project slightly through said aperture. In the edge of the rim B is formed a groove, *x*, as shown. Within the rim B is formed a circular box, C, concentric therewith, and within said box, around the inside, is placed a series of rollers, D D. The rim or box C and rollers D are of less height than the rim B. G represents a wheel placed within the rim B, and formed with an annular recess, *b*, in one side, which leaves a rim, *a*, around the periphery, and a hub, *d*, in the center. The hub *d* is of such size as to just fit within the circle described by the friction-

rollers D D, so that all the weight and strain will come on said hub, rollers, and the box inclosing the rollers. This box is stationary, so that the rollers and wheel are the only rotating portions of the device. In casting the hangers it will thus be seen that it is these parts only that have to be of such size as to carry the weight. The other parts may be made comparatively light.

The wheel G is held in place by a cap or plate, H, having on its inner side, around the periphery, a flange or bead, *y*, to fit in the groove *x* on the rim B, and also a flange, *i*, to fit in the opening *h*, leaving, however, room enough for the wheel in said opening to run upon the bar or beam that supports the door.

A central bolt, *m*, with nut *n*, secures the parts firmly together.

When this hanger is secured to the door and suspended on the bar or beam at the top, the entire weight is on the rollers D D, and, these being placed free within the box C, there is but little friction, and hence the door can be moved freely and easily in either direction.

We are aware of United States Patent No. 175,243, and do not, broadly, claim anything shown therein; but,

Having thus fully described our invention, what we claim as new, and desire to secure by Letters Patent, is—

The wheel G, having rim *a*, annular recess *b*, and hub *d*, in combination with strap A, having rim B, and circular box C, and the friction-rollers D, and with the cap piece H, all constructed and arranged substantially as and for the purpose set forth.

In testimony that we claim the foregoing as our own we affix our signatures in presence of two witnesses.

SAMUEL H. MOORE.
EDWARD Y. MOORE.
